DESIGN FOR A DESK ORNAMENT OR THE LIKE

Howard J. Agnew, Arkansas City, Kans.

Application March 8, 1939, Serial No. 83,439

Term of patent 7 years

To all whom it may concern:

Be it known that I, Howard J. Agnew, a citizen of the United States, residing at Arkansas City, in the county of Cowley and State of Kansas, have invented a new, original, and ornamental Design for a Desk Ornament or the like, of which the following is a specification, reference being had to the accompanying drawing, forming part thereof.

I claim:

The ornamental design for a desk ornament or the like, as shown.

HOWARD J. AGNEW.
